INVENTOR

UNITED STATES PATENT OFFICE.

LOUIS LEVINE, OF BROOKLYN, NEW YORK.

DESIGN FOR A LIGHTING-FIXTURE ARM.

61,201.

Specification for Design.

Patented July 11, 1922.

Application filed October 8, 1921. Serial No. 506,529. Term of patent 7 years.

To all whom it may concern:

Be it known that I, LOUIS LEVINE, a subject of the Empire of Russia, and a resident of the city of New York, borough of Brooklyn, in the county of Kings and State of New York, have invented a new, original, and ornamental Design for a Lighting-Fixture Arm, of which the following is a specification, reference being had to the accompanying drawing, forming part thereof.

In the accompanying drawing:—

Figure 1 is a plain view of a lighting fixture-arm showing my new design.

Figure 2 is a side view.

I claim:

The ornamental design for a lighting fixture-arm, as shown.

LOUIS LEVINE.
